UNITED STATES PATENT OFFICE

135,554

DESIGN FOR A CIRCULATING HEATER

Edward J. Burke, Richmond, Va., assignor to
Southern Stove Works, Inc., Richmond, Va.

Application September 24, 1942, Serial No. 108,323

Term of patent 7 years

To all whom it may concern:

Be it known that I, Edward J. Burke, a citizen of the United States, residing at Richmond, in the county of Henrico and State of Virginia, have invented a new, original, and ornamental Design for Circulating Heater, of which the following is a specification, reference being had to the accompanying drawing forming part thereof.

In the drawing:

Figure 1 is a perspective view of a circulating heater embodying my new design; and

Figure 2 is a front elevational view thereof on a reduced scale.

The grille is shown only on part of the front

panels in Figure 2, but it is to be understood that it continues throughout the panel areas as in Figure 1.

The dominant features of the design reside in configuration of the front, comprising the top front panel, the bottom front panel with the vertical parallel bars extending therebetween, which as a unit stand out in relief from the plane of the adjacent lateral panels as shown.

Both ends of the heater are alike and the back is plain.

I claim:

The ornamental design for a circulating heater, as shown and described.

EDWARD J. BURKE.
